UNITED STATES PATENT OFFICE.

HENRY HELLMAN AND LEWIS CONDICT BAYLES, OF JOHANNESBURG,
TRANSVAAL.

ROCK-DRILLING MACHINE OR ENGINE.

No. 834,522.

Specification of Letters Patent.

Patented Oct. 30, 1906.

Application filed January 11, 1905. Serial No. 240,661.

To all whom it may concern:

Be it known that we, HENRY HELLMAN and LEWIS CONDICT BAYLES, citizens of the United States, residing at Johannesburg, 5 Transvaal, have invented certain new and useful Improvements in Rock-Drilling Machines or Engines, of which the following is a specification.

Our present invention consists of improvements in and relating to rock-drilling machines or engines intended for use in mining work for the boring of holes for the reception of explosive charges for displacing or breaking away the rock or mineral.

15 The improvements are more particularly designed for machines or engines constructed to operate in the manner described in a previous application for patent filed by us on the 10th day of August, 1904, and bearing 20 Serial No. 220,176.

The main objects of the present improvements are, first, to provide improved means for introducing the motive fluid into the machine; secondly, to provide means for preventing the ingress into the machine of impurities or particles of solid matter that may be suspended in or carried by the motive fluid; thirdly, to provide mechanism which will operate to release the rotating gear during the operation of returning the machine; fourthly, to provide an arrangement whereby the column, column-clamp, and base-block are all adjustably attached and secured by means of keys or to obviate the use of 35 screws or like contrivances, and thereby enable the mounting and dismounting to be effected with greater facility, and, fifthly, to the general construction, arrangement, and combination of parts, as hereinafter particularly described, and pointed out in the appended claims.

A rock-drilling machine or engine constructed in accordance with our present invention is compact or of comparatively 45 small dimensions, the operative parts are all completely inclosed and protected, and it is more easily manipulated and erected or dismounted than existing machines.

The valve or means for controlling the admission of the motive fluid alternately to either end of the power-cylinder do not in themselves form any part of the present invention, and they may be of any suitable construction. The admission of said motive

fluid may be controlled by means of a valve 55 or by means of the piston or reciprocating percussive member.

In order that the invention may be readily understood, we append an explanatory sheet of drawings marked with characters of 60 reference corresponding to the following description thereof, and in which—

Figure 1 represents a longitudinal part-sectional elevation of the machine mounted on the column. Fig. 2 is a transverse section 65 on line $x-x$, Fig. 1. Fig. 3 is a transverse section on line $z-z$, Fig. 1. Fig. 4 is a transverse section on line $y-y$, Fig. 1. Fig. 5 is a transverse section on line $x-y$, Fig. 1. Fig. 6 is a transverse section on line $x-z$, Fig. 1. Fig. 7 70 is a section taken through the column-base on line $y-z$, Fig. 1; and Fig. 8 is a sectional plan taken through the column on line $y'-z'$, Fig. 1. Fig. 9 is a sectional plan view showing the rods 16 and 17 and gearing connected 75 therewith.

As illustrated, the machine proper comprises the power-cylinder 1, which is slidably mounted in an outer preferably cylindrical protecting-easing 2.

The power-cylinder 1 is at its forward end fitted with the cap or cover 3. 4 represents the drilling-bit or boring-tool, which may, if desired, be formed with the longitudinal hole 4^a to permit a quantity of the actuating fluid 85 to pass to the cutting-face of the tool to blow away the rock-cuttings.

The shank end 5 of the tool 4 is of square or polygonal transverse section, and the hole 6, formed in the cap 3, is of corresponding shape 90 to receive it. As the cylinder 1 is rotated the tool 4 is compelled to rotate in unison therewith, while it is free to move longitudinally of the cylinder 1 in the operation of the machine.

7 is the piston or reciprocating percussive member located in the cylinder 1, which member at the end of its forward stroke strikes directly on the end of that part of the shank 5 which projects into the bore of the cylinder 1.

9 represents the port formed in the cylinder 1, along which the actuating fluid passes to the forward end of the cylinder to impel the piston 7 on its rearward stroke; and 10 is 100 a port which by allowing the motive fluid to escape from the forward end of the cylinder 1 prevents the reversal of the piston 7 should it

from any cause overrun the actuating-fluid-supply port 9.

11 is the cover fitted in the forward end of the protecting-casing 2. The power-cylinder 1 is arranged eccentrically in the casing 2 and is slidably supported at the forward end by the cover 11.

In the rear end of the protecting-casing 2 is fitted a cover 12, in which is journaled a 10 spindle 13, fitted on the outer end with a handle or crank 14. On the inner end of the spindle 13, inside the casing 2, is fixed a toothed wheel 15. (See Figs. 1 and 2.) The rotation of this toothed wheel 15 by means of 15 the crank 14 effects the dual operation of feeding the drill or moving the power-cylinder 1 forward in its protecting-casing 2 as the tool 4 penetrates the rock and also the rotation of the power-cylinder 1, and with it the 20 bit or tool 4. The means we employ for effecting the rotation of the bit or tool 4 and the feeding of the machine are the same as those described in our previous application, Serial No. 220,176. Part of this mechanism 25 is illustrated in Figs. 1, 2, and 3, and it consists of two parallel rods 16 17, (see Figs. 2 and 3,) arranged longitudinally of the casing 2, journaled in bearings provided in the covers 11 12, on which rods 16 17 are fixed the 30 pinions 18 19, which gear with the toothed wheel 15 on the spindle 13. One of these rods 16 has keyed to it another pinion 20, which is slidable longitudinally (see Fig. 4) and which gears with a toothed wheel 21, 35 mounted on the rear end of the power-cylinder 1 or an extension 22 of the valve-box cap 23, which is fitted to the rear end of the power-cylinder 1. In the center of the pinion 20 is fixed a feather-key which slides in a feather- 40 way in the rod 16, so that it may move longitudinally of the rod, while being compelled to rotate with it. The other rod 17 (see Figs. 3 and 4) is formed with a screw-thread which works through a nut 24, carried by the 45 swivel-piece 25. The rod 16 through the pinions 18 and 20 serves to rotate the power-cylinder 1, and with it the bit 4, through the toothed wheel 21, while the other and screwed rod 17 serves to traverse the power- 50 cylinder 1 longitudinally of the outer and protecting casing 2 through the feed-nut 24.

In order to illustrate the present improvements more clearly, the rods 16 17, pinions 18 19, and pinion 20 are not shown in Fig. 1 of the drawings.

In the rear cover 12 of the protecting-casing 2 is formed the intake or air-inlet 26. With the object of preventing the admission into the machine of any particles of solid 60 matter that may be carried by the actuating fluid we arrange in the intake a gauze strainer 27, which in the form illustrated in Fig. 1 consists of a cone of gauze of a suitably fine mesh. The base of the cone is soldered 65 or otherwise fixed to a screwed ring 28, which

ring is screwed up into the intake 26 for a suitable distance. While we illustrate the gauze strainer 27 in this position, it will be evident that it might be located in any position between the intake 26 and cylinder. 70 By the conical shape of the strainer 27 we find that a larger volume of the actuating fluid can be passed through the intake 26 than is possible when a disk or flat strainer of equal diameter is employed. Instead of constructing the strainer of conical shape it will be evident that it may be made hemispherical or of other concavo-convex form. 75

For the purpose of conducting the actuating fluid from the inlet 26 to the cylinder 80 we provide an arrangement comprising a longitudinally-arranged tube 29, which at its rear end is fixed in the back cover 12 and communicates with the inlet 26. Encircling the tube 29 is a pipe 30, which at its forward 85 end is closed and at its rear end is fitted with a cap 31 and jam-nut 32 in such manner that it can slide longitudinally of the tube 29, and 33 is a cup-leather fitted in the cap 31 between the end of the pipe 30 and the tube 29 to prevent the escape at that point of the actuating fluid. The pipe 30 is formed with an external screw-thread for a portion of its length, and it is fixed to and carried by the swivel-piece 25 by screwing it into a hole (see 90 Fig. 3) in the bottom of said swivel-piece 25. 34 35 are jam-nuts on the pipe 30 at either side of the swivel-piece 25, which serve to secure it in position. In the pipe 30 is formed a hole 36, which latter communicates with a 95 passage 37 in communication with the annular chamber 38, formed inside the swivel-piece 25. The annular chamber 38 is placed in communication with the valve-box through the transverse hole 39, formed through the 100 valve-box cap extension 22. The motive fluid in its passage from the intake 26 to the valve-box passes through the gauze strainer 27, then along the tube 29 into the pipe 30, and through the hole 36 and along the passage 37 into the annular chamber 38, whence it passes by the transverse hole 39 into the valve-box inside the valve-box cap 23. 40 41 represent cup-leathers fitted in each side of the swivel-piece 25, and 42 is a ring or annular plate arranged between the toothed wheel 21 and the swivel-piece 25. The valve, 45 when one is employed, operates to admit the motive fluid alternately to either end of the power-cylinder 1 or either side of the piston or per- 50 spective reciprocating member 7, which latter on its forward stroke strikes the inner end of the shank 5 of the bit or tool 4. 55

In the forward cover 11 of the protecting-casing 2 is formed a hole 43, through which the pipe 30 projects as the power-cylinder 1 is fed forward in the casing 2.

As previously explained, the pinion 20 on the longitudinally-arranged rod 16 meshes with the toothed wheel 21, which is mounted 130

on the rear end of the valve-box-cap extension 22 and serves for rotating the power-cylinder 1, and with it the bit or tool 4. In order to release this gear or prevent rotation 5 of the bit or tool during the operation of returning the machine, a cylindrical piece or cam 44 (see Figs. 1 and 4) is keyed or otherwise securely fixed on the valve-box-cap extension 22 inside the boss or center of the toothed wheel 21. This cylinder 44, as shown more particularly in Fig. 4, is formed with four (more or less) external wings or projections, which form four curved and tapering recesses 45 between the outside of the cylinder 44 and the inside of the boss or center of the toothed wheel 21. In these 15 four recesses 45 are located four (more or less) rollers 46, whose axes are parallel with the axis of the power-cylinder 1. When the toothed wheel 21 is rotated by the pinion 20 in the direction indicated by the arrow in Fig. 4, the rollers 46 ride up the inclines formed by the tapering recesses 45 and bind the toothed wheel 21 to the cylinder 44, so 20 that the toothed wheel 21 as it rotates carries with it the cylinder 1 and bit or tool 4. When the toothed wheel 21 is rotated in the reverse direction, it moves the rollers 46 down the inclines until they engage the projections, 25 which allows the inside of the toothed wheel 21 to run freely round the cylinder 44.

The cylinder 44, rollers 46, and toothed wheel 21 are maintained in position on the valve-box-cap extension 22 by means of the ring or plate 47 and nut 48, screwed on the outer extremity of the valve-box-cap extension 22.

In Fig. 1 the outer protecting-casing 2 is shown carried by the sleeve 49, formed with 40 a central transverse slot in which is fitted a ring 50, formed with a recess to receive a wedge or taper key 51, between which sleeve 49 and ring 50 the protecting-casing 2 is secured by driving in the key 51. This arrangement is illustrated and described in our prior 45 application, Serial No. 220,176.

52 represents the column; 53, the column-nut; 54, the jack-screw; 55, the base, and 56 the base-block. On the column 52 is ad- 50 justably mounted the column-clamp 57, (see Fig. 8,) which has attached to it the sleeve 49. The sleeve 49 is formed with the cylindrical projection 58, which fits into a hole in the column-clamp 57. A keyway is formed 55 through the column-clamp 57, passing down one side of the projection 58. In the keyway is arranged a gib 59, which projects against the cylindrical extension 58. In the keyway at the back of the gib 59 is placed 60 the key 60, which when driven in one direction forces the gib 59 inward to grip the cylindrical projection 58, and so fixes the sleeve 49 to the column-clamp 57. The column-clamp 57 is fixed to the column 52 in a similar 65 manner to the sleeve 49 by means of a

gib 61 and key 62. (See Fig. 8.) The lower end of the jack-screw 54 is secured in the base 55 in like manner by means of the gib 63 and key 64. (See Fig. 7.) By this construction the several parts are adjustably secured by means of the keys, so that all that is necessary to adjust the machine vertically on the column 52 or to dismantle it is to drive the several keys in the direction to disengage the gibs, which construction allows these several operations to be performed much more quickly than at present.

What we claim as our invention, and desire to protect by Letters Patent, is—

1. In a rock-drilling machine or engine, in combination, a power-cylinder carrying a pipe in open communication therewith and an outer protecting-casing in which said cylinder is slidably mounted, a cover at the rear end of said protecting-casing, an actuating-fluid inlet or intake formed in said cover, a tube in communication with said intake, and slidably engaging with the pipe aforesaid, and packing between said pipe and said tube.

2. In a rock-drilling machine or engine, in combination, a power-cylinder carrying at its rear end a pipe in open communication therewith and adapted to move longitudinally therewith in either direction and an outer protecting-casing, a cover at the rear end of said protecting-casing, an actuating-fluid inlet formed in said cover, a tube in communication with said actuating-fluid inlet and slidably engaging with the pipe aforesaid and packing between said pipe and said tube.

3. In a rock-drilling machine or engine, a power-cylinder carrying percussive apparatus, and a pipe carried by said power-cylinder, in combination with a casing surrounding said power-cylinder, a cover fitted in the rear end of said casing provided with an actuating-fluid inlet, a tube fitted in said cover communicating at one end with the actuating-fluid inlet and slidably engaging with the pipe carried by the power-cylinder, and packing between said pipe and said tube, and said pipe being in communication with the power-cylinder for conducting the actuating fluid from the inlet to said cylinder, substantially as described.

4. In a rock-drilling machine, or engine, a power-cylinder carrying percussive apparatus and a drilling bit or tool, a protecting-casing surrounding said cylinder, a cover fitted in the rear end of said casing provided with an actuating-fluid inlet, a tube fitted in said cover communicating at one end with the actuating-fluid inlet, a pipe surrounding and spaced away from said tube closed at its forward end and adapted to slide longitudinally of said tube, packing between said pipe and said tube, a swivel-piece mounted at the rear end of the cylinder carrying the pipe, said swivel being constructed with ports

which place the pipe in communication with the inlet to said power-cylinder, substantially as described.

5. In a rock-drilling machine or engine, in combination, a power-cylinder carrying percussive apparatus and a drilling bit or tool, means for compelling said drill or bit to rotate in unison with the power-cylinder, a toothed wheel carried by the power-cylinder, a pinion in gear with said toothed wheel, means for rotating said pinion, a cylindrical piece fixed at the rear of the power-cylinder constructed with projections forming tapering recesses inside the toothed wheel, and rollers arranged in said recesses which operate to lock the cylinder to the toothed wheel when the latter is moved in one direction and to allow the toothed wheel to rotate freely on the cylinder when it is moved in the opposite direction, substantially as described. 15

6. In a rock-drilling machine or engine, in combination, a power-cylinder carrying percussive apparatus and a drilling bit or tool, means for compelling said bit or tool to rotate in unison with the power-cylinder, a toothed wheel mounted on the rear end of the cylinder, a pinion in gear with said toothed wheel and means for rotating said pinion, a cylindrical piece fixed to the rear end of the cylinder and means for locking said cylindrical piece to the toothed wheel when the latter is moved in one direction while permitting the toothed wheel to rotate independently in the reverse direction so that the 20 power-cylinder and drill or bit are rotated through the medium of the toothed wheel when the latter is rotated in one direction, substantially as described. 25

7. In a rock-drilling machine or engine, in combination, a power-cylinder carrying percussive apparatus and a drilling bit or tool, 30

means for compelling the bit or tool to rotate in unison with the power-cylinder, a toothed wheel carried at the rear end of the power-cylinder, a pinion in gear with said toothed wheel, means for rotating said pinion, a cylindrical piece fixed at the rear of the power-cylinder constructed with projections forming tapering recesses inside the toothed wheel, and rollers arranged in said recesses which 40 operate to lock the cylinder to the toothed wheel when the latter is moved in one direction and to allow the toothed wheel to rotate freely on the cylinder when it is moved in the opposite direction, substantially as described. 45

8. In a rock-drilling machine or engine, in combination, a power-cylinder carrying percussive apparatus and a drilling bit or tool, means for compelling the latter to rotate with the cylinder, means arranged at the rear 50 end of said cylinder for conducting the actuating fluid to the interior of said cylinder, means located at the rear of said cylinder for rotating the cylinder and with it the drilling bit or tool as the latter is fed forward and for 55 allowing the cylinder to be returned without rotation, and means for simultaneously rotating the cylinder and feeding the drill, substantially as described.

In testimony whereof we have signed our 60 names to this specification in the presence of two subscribing witnesses.
